UNITED STATES PATENT OFFICE.

ROSCOE E. OVERMAN, OF LOS ANGELES, CALIFORNIA.

DRILL.

Application filed October 26, 1920. Serial No. 419,577.

To all whom it may concern:

Be it known that I, ROSCOE E. OVERMAN, a citizen of the United States, residing at Los Angeles, in the county of Los Angeles and State of California, have invented new and useful Improvements in Drills, of which the following is a specification.

This invention relates to a drill and an object thereof is to provide a drill which is especially adapted for use in well drilling operations and more particularly employed in sinking tubular well casings as in drilling for oil or water.

Another object is to provide a well drilling tool of the rotary type embodying a series of revoluble elements on the tip thereof so constructed and arranged as to effect a cutting action by crushing and finely comminuting the materials worked upon so that the debris may be readily discharged in water.

Another object is to provide the tool with crushing and grinding rolls so arranged relative to each other and to the vertical axis of rotation of the tool whereby the material acted on thereby will be not only finely ground but also thoroughly admixed with water so that the water and the solids may be readily removed.

Another object is to provide the tool with grinding rolls which are renewable and interchangeable and which may be readily removed and replaced when worn.

Another object is to provide a tool of the above character which is so constructed as to insure drilling a straight hole, which is rapid in operation, and adapted for use in various formations.

A further object is to provide the tool with an arrangement of boring rolls whereby an undercutting action may be readily effected, and embodying means whereby the tool may be expanded and contracted.

Other objects will appear hereinafter.

The invention is illustrated in the accompanying drawing, in which:

Figure 1 is a view showing a well casing in section with the tool disposed therein in its contracted position.

Figure 2 is a view in elevation of the tool in its expanded position.

Figure 3 is a view in side elevation of the tool.

Figure 4 is an end view showing the arrangement of the boring rolls.

Figure 5 is a view in cross section as seen on the line 5—5 of Figure 2.

Figure 6 is a view in section of one of the rolls.

More specifically, 5 indicates the shank 60 of the drill the lower portion of which is wedge shape in form to provide inclined or tapered side walls 6 on opposite sides thereof, the end walls 7 of the shank being straight and parallel. The upper portion of 65 the shank converges into a square stem 8 fitted with an annular flange 9 forming the upper end of the shank, and on which flange is formed a tapered threaded portion 10 which is adapted to be screwed into the lower 70 end of a tubular drill rod 11 by which the drill is suspended and operated, as is common in rotary drill operation. The shank is formed with a longitudinal bore 12 extending throughout the length thereof 75 and communicating with the interior of the drill rod 11 thru which water may be passed downwardly and discharged from the lower end of the drill centrally thereof. Formed on the inclined sides of the shank 5 are dove 80 tail ribs 13 which extend longitudinally of the shank and are adapted to engage dove tail grooves formed on the inner inclined faces of a pair of slips 14 which are designed to be slidably mounted on the inclined faces of the shank. The sides of the slips are preferably flush with the flat end faces 7 of the shank, as shown in Figure 5, 85 so that the slips and shank will have a corresponding width, and formed on the sides 90 of the slips are vertically extending channels 15 into which the ends of a cross bar 16 projects; a cross bar 16 being mounted on each flat side of the shank and countersunk therein. These cross bars are designed to 95 limit the longitudinal movement of the slips and shank relative to each other and are adapted to engage the upper ends of the channels 15, as shown in Figure 1, or to abut against the lower ends of the channel, 100 as shown in Figure 2, according to whether the slips are contracted or expanded relative to each other on the shank as will be later described.

Mounted on the lower end of the shank 105 is a pair of complementary rollers 17 and 18 revoluble on a shaft 19 supported in projections 20 in the end of the shank, and mounted on the end of each slip is a roller 21 which is designed to rotate on a shaft 22 110

carried by a hanger 23 and a plate 24 mounted on the slip.

As a means for affording a substantial mounting for the shafts and the rollers thereon, the projections 20 and the plates 24 are formed with inwardly extending collars 25 which project into recesses 26 in the outer ends of the rollers 17, 18, and 21 so the rollers will extend close to the edges of the shank and slips and the shaft bearings will not project materially beyond the outer faces thereof; this construction providing wide bearings for the shaft. One of the collars 25 supporting the shaft 19 and the collars 15 on the plates 24 are internally threaded, as shown in Figure 6, and the shafts are screwed into engagement therewith to permit ready removal and replacement of the shafts and rollers. The rollers are provided 20 with bushings 27 which extend from their inner ends to the shoulders formed by the recesses 26.

The rollers 17, 18, and 21 are preferably of corresponding construction and are here 25 shown as tapered and disposed with their larger diameters outermost. The rollers are formed with peripheral ribs and channels or corrugations so as to adapt the rollers to have a crushing and grinding action on rotation of the drill. The rollers 21 are preferably arranged diagonally to the rollers 17 and 18 and to their arcuate path of travel with their axes offset but in parallel relation to each other, as particularly shown in 30 Figure 4, so that when the drill is rotated with the rollers 21 bearing on a surface these rollers will both rotate and slide in traversing the surface to effect a crushing and grinding action thereon. The rollers 21 are 35 arranged so that a portion of their enlarged outer ends on these horizontal diameters will project diagonally beyond the outer faces of the slips so that on rotation of the drill they will cut a bore of a diameter 40 greater than that of the combined slips and shank and thereby afford clearance between the walls of the bore and the slips. This bore is cut under the lower end of the casing to permit the latter being lowered therein. 45 In the operation of the invention, the slips are advanced on the shank so that they will extend beyond the lower end thereof, in which position they will be contracted relative to each other by 50 reason of the inclination or taper of their slide mounting. When thus disposed the slips will be supported on the cross bars 16. The drill may then be raised or lowered through the well casing 28, as shown in 55 Figure 1. When the slips come to rest on the bottom of the bore the shank may be lower between the slips and by reason of its wedge shape cause the slips to move outwardly into their expanded position below 60 the lower end of the casing. When the shank 65

is in its lowermost position between the slips, the cross bar 16 will abut against the lower ends of the channels 15 so that the shank of the drill and the load imposed thereon will bear upon the slips. The shank and slips 70 are so proportioned that when the shank is in its lowermost position between the slips, the several rollers will be positioned on substantially the same plane.

On rotation of the drill the rollers 17 75 and 18 will rotate on their shaft in opposite directions and in extending diametrically across the axis of rotation of the drill will form the central portion of the bore. The rollers 21 being arranged with their outer 80 ends disposed beyond the path of travel of the outer ends of the inner rollers 17 and 18 will act to form the walls of the bore. The boring action of the drill consists in crushing and grinding the materials acted on by 85 the rollers rather than by cutting, which action is facilitated by reason of the drill being heavily weighted and by the corrugated formation of the rollers thus adapting the tool for use in various formations. 90 The materials acted on by the rollers being finely ground will be thoroughly commingled with the water delivered to the lower end of the drill through the shank and drill rod so that the debris may be readily 95 removed on discharging the water from the bore.

By forming the several rollers of corresponding size and construction they may be interchanged and it is only necessary to 100 construct one size of roller to equip a drill. However, the drills will be constructed of various sizes according to the diameter of the bore to be formed and each size of drills may have rollers of a size to correspond 105 thereto.

I claim:

1. A drill comprising a wedge-shaped shank formed with a longitudinal bore and having dove-tail ribs extending lengthwise 110 of its inclined sides, a tapered slip formed with a dove-tail slot on its inclined face slidably engaging the dove-tail rib on the shank, a slip being mounted on each inclined face of the shank, means for limiting longitudinal movement of the slips and shank relative to each other, a pair of axially aligned crushing rollers on the lower end of the shank, and a complementary crushing roller on the lower end of each slip. 115

2. A drill comprising a wedge-shaped shank formed with a longitudinal bore and having dove-tail ribs extending lengthwise 120 of its inclined sides, a tapered slip formed with a dove-tail slot on its inclined face slidably engaging the dove-tail rib on the shank, a slip being mounted on each inclined face of the shank, means for limiting longitudinal movement of the slips and shank relative to each other, a pair of ax- 125

ially aligned crushing rollers on the lower end of the shank, a complementary crushing roller on the lower end of each slip diagonally arranged relative to the rollers on the shank, and disposed substantially in parallel relation to each other.

3. A drill comprising a wedge-shaped shank formed with a longitudinal bore and having dove-tail ribs extending lengthwise 10 of its inclined sides, a tapered slip formed with a dove-tail slot on its inclined face slidably engaging the dove-tail rib on the shank, a slip being mounted on each inclined face of the shank, means for limiting 15 longitudinal movement of the slips and shank relative to each other, a pair of axially aligned crushing rollers on the lower end of the shank, and a complementary crushing roller on the lower end of each 20 slip, each of said rollers being tapered and formed with peripheral ribs and grooves.

4. In a drill, a shank, a pair of slips slideable lengthwise thereon, a pair of axially aligned crushing rollers on the end of the 25 shank, and a crushing roller on the end of each slip arranged so that a portion of the roller on its horizontal diameter at its outer

end will project beyond the outer face of the slip.

5. In a drill, a shank, a pair of slips slideable lengthwise thereon, a pair of axially aligned crushing rollers on the end of the shank, a crushing roller on the end of each slip, the rollers on the slips arranged diagonally with respect to the rollers on the shank and to their path of travel on rotation of the shank.

6. In a drill, a shank, a pair of slips slideable lengthwise thereon, a pair of axially aligned crushing rollers on the end of the shank, a crushing roller on the end of each slip, the rollers on the slips arranged diagonally with respect to the rollers on the shank and to their path of travel on rotation of the shank, said rollers being tapered and having peripheral corrugations.

7. In a drill, a crushing roller having a recessed outer end, a shaft on which the roller is revoluble, a pair of supports on said shaft, one of said supports embodying a collar projecting into the recess and with which the shaft has screw thread engagement.

ROSCOE E. OVERMAN.
